ELECTRICAL MEDICINAL VAPORIZER OR THE LIKE

Donald B. Lowe, Jr., Batavia, Ill., assignor to Northern Electric Company, Chicago, Ill., a corporation of Delaware

Filed June 23, 1960, Ser. No. 61,095

Term of patent 14 years

(Cl. D83—1)

Fig. 1

Fig. 2

Fig. 3Fig. 4Figure 1 is a perspective view of an electrical medicinal vaporizer or the like, showing my new design;

Figure 3 is a front elevational view thereof on an enlarged scale, the top being omitted for convenience of illustration, and a portion of the side and the handle being shown in section; and

The dominant features of my design reside in the full line portions of the drawing.

This application is a continuation-in-part of my co-pending application, D-56,411, filed June 18, 1959, now abandoned.

I claim:

The ornamental design for an electrical medicinal vaporizer or the like, substantially as shown and described.
